UNITED STATES PATENT OFFICE.

EDMOND REDMOND, OF ROCHESTER, NEW YORK.

NAIL-EXTRACTOR.

968,688.

Specification of Letters Patent. Patented Aug. 30, 1910.

Application filed February 21, 1910. Serial No. 545,241.

To all whom it may concern:

Be it known that I, EDMOND REDMOND, a citizen of the United States, residing at Rochester, in the county of Monroe and State of New York, have invented a new and useful Nail-Extractor, of which the following is a specification.

My invention relates to devices for extracting nails from and driving nails into boards, etc., and is designed as a substitute for the more expensive ones now in common use.

My invention enables one to draw out a nail noiselessly and without breaking the wood around the head as much as by the old means. It also serves to drive out a nail or spike when the point thereof protrudes from a plank, etc.; it can be employed to extract nails that have been clenched.

In the drawings Figure 1 is a side elevation; Fig. 2 is a horizontal section taken substantially on line *a—a* Fig. 1; Fig. 3 is a front elevation of the adjustable claw; and Fig. 4 is a vertical section taken on the line *b—b* of Fig. 2.

My invention consists of a tube A, a plunger B fitted loosely in the tube, and a movable claw E adjustable on the tube. The edge of the tube on one end is sharpened and provided with a cleft D like that in ordinary tack pullers. In use the sharp edge of the tube is to be employed as a gouge to cut away the wood at the head of the nail, or to pry up the point of a clenched nail, which can then be drawn by setting the cleft in the tube under the nail head and prying on it with the tube as a lever. When the nail has been started it can be pulled out by means of the claw at the end of the tube altogether by putting a fulcrum block, as a block of wood, under the tube-lever, or by

means of the movable claw on the tube, using the latter as a lever to lift the nail.

To employ the device for driving back a protruding nail, the tube is placed over the point of the nail and the plunger driven down on the nail. The end of the plunger is provided with a cavity C into which the point of the nail will fit and thereby prevented from being blunted while being driven out. The tube, its bore being but a little greater than the diameter of the nail, will prevent the nail bending under the blows employed to drive it back.

The plunger is to be expanded on the end within the tube a little more than its mean diameter. When it is inserted in the tube, the latter is to be closed enough on its upper end to catch the expansion on the end of the plunger and prevent it from pulling out of the tube, but not to prevent its easy movement in the tube.

The device can be employed to drive nails into hard wood, for the tube will prevent the nails from bending under blows that would distort them if not supported by the wall of the tube.

Having fully described my invention, what I claim and desire to secure by Letters Patent is:

In a nail extractor the combination of a tube and plunger, one end of the tube having a sharp edge whereby to pry up a clenched nail; the plunger containing a cavity in its end to receive the point of a nail in the process of driving it out; the plunger and tube provided with means to prevent them separating.

EDMOND REDMOND.
